MUDDLER

Koji Mori, 14 3-Cho Ebisunocho, Sakai, Osaka, Japan

Filed Apr. 7, 1960, Ser. No. 60,153

Term of patent 14 years

(Cl. D44—29)

Figure 1 is a side elevation of the muddler showing my new design.

Figure 2 is a top plan view of the same.

The facets of the handle opposite those shown in Fig. 1 are substantially similar in ornamentation thereon.

I claim:

The ornamental design for a muddler, substantially as shown and described.
